UNITED STATES PATENT OFFICE.

RICHARD S. CHAPMAN, OF PRINCETON, MINNESOTA.

FOOT-REST ATTACHMENT FOR RADIATORS.

1,237,749.

Specification of Letters Patent. Patented Aug. 21, 1917.

Application filed April 3, 1916. Serial No. 88,514.

To all whom it may concern:

Be it known that I, RICHARD S. CHAPMAN, a citizen of the United States, residing at Princeton, in the county of Millelacs and 5 State of Minnesota, have invented certain new and useful Improvements in Foot-Rest Attachments for Radiators; and I do hereby declare the following to be a full, clear, and exact description of the invention, such as 10 will enable others skilled in the art to which it appertains to make and use the same.

My invention has for its object to provide a foot rest attachment for radiators; and, to this end, it consists of the novel devices 15 and combinations of devices hereinafter described and defined in the claims.

In the accompanying drawings, which illustrate the invention, like characters indicate like parts throughout the several views.

20 Referring to the drawings,

Figure 1 is a view, principally in plan illustrating the foot rest moved into an inoperative position, some parts of the radiator being shown in section;

25 Fig. 2 is a transverse vertical section taken on the line $x^2 x^2$ of Fig. 1;

Fig. 3 is a fragmentary detail view with some parts shown in longitudinal section taken on the line $x^3 x^3$ of Fig. 2;

30 Fig. 4 is a fragmentary detail view in transverse section taken on the line $x^4 x^4$ of Fig. 3; and

Fig. 5 is a transverse section taken on the line $x^5 x^5$ of Fig. 2.

35 The steam radiator shown is made up of a plurality of two column sections 1 connected at their lower extremities by couplings 2, which afford a conduit between the several sections of the radiator.

40 The foot rest attachment comprises a horizontal tubular rail 3 carried by a pair of laterally spaced segmental arms mounted for vertical swinging movement between certain sections of the radiator. As shown,

45 each supporting arm 4 is formed from a pair of sheet metal plates rigidly connected by rivets and having outwardly extended marginally reinforcing ribs 5 pressed therefrom. The lower end of each arm 4 has

50 formed therein a segmental notch or open seat 6 that straddles and bears upon one of the couplings 2, which affords a pivotal support therefor. Formed in the upper segmental edge of each arm 4, is a plurality of cir-

55 cumferentially spaced lock notches 7 and an open seat 8. These seats 8 are consider-

ably wider than the arms 4, are axially alined and receive and support the foot rail 3.

Pairs of wing nut-equipped bolts 9 detachably and adjustably connect the foot rail 3 to each arm 4. These bolts 9 are slidably mounted in a longitudinally extended slot 10 formed in the foot rail 3, with their heads located in said foot rail and with their screw-threaded ends projecting through holes formed in the seats 8, as best shown in Fig. 4. To prevent rotation of the bolts 9 and endwise movement into the foot rail 3, during the application or the removal of their wing nuts, said bolts have a diameter 65 slightly larger than the width of the slot 10 and are flattened on opposite sides to permit the same to enter the slot 10.

A pair of spring latches 11 are anchored to the radiator for securing the supporting 75 arms 4 in different set adjustments. One of these latches 11 yieldingly rides upon the periphery of each arm 4 and is provided with a lock lug 12, adapted to enter and interlock with any one of the lock notches 7 in the respective arm 4. The spring latch 11 is detachably and adjustably secured to the two radiator sections 1, between which the respective arm 4 vertically swings by a clamp comprising a pair of wedge blocks 80 13 connected for horizontal movement by a long draw bolt 14. These wedge blocks 13 are located above the arms 4 and extend between the outer columns of the respective radiator sections and are frictionally 85 clamped thereon by the draw bolts 14. The draw bolts 14 have free endwise sliding movement through the outer wedge blocks 13 and have screw-threaded engagement with the inner of said wedge blocks. The spring 90 latches 11 are secured to the inner wedge blocks 13, as best shown in Fig. 2, and have formed on their upper outer end portions, ratchet teeth 15. The spring latches 11 are held against accidental lifting movement 95 by keys 16 mounted for oblique sliding movement in the outer wedge blocks 13 and engaging the ratchet teeth 15, under the action of gravity. As shown, each key 16 is of rectangular skeleton form with its side members slidably mounted in oblique holes 17 formed in the outer wedge members 13.

The ribs 5 not only reinforce the arms 4, but hold the same against lateral movement between the respective radiator sections and 110 prevent rattling thereof. In case the ribs are not wide enough to substantially fill the

space between the respective radiator sections, one or more supplemental ribs 18 may be applied to the inner longitudinal rib of each arm 4. These supplemental ribs 18 may be secured in position by rivets or other suitable means.

It is, of course, evident that the arms 4 and clamp 13-14 may be applied between any of the sections of the radiator, and the foot rail 3 may be of any desired length.

The above described invention, while extremely simple and of comparatively small cost to manufacture, has, in actual usage, proven highly efficient for the purpose had in view.

What I claim is:-

1. The combination with a radiator, of a foot rest pivotally supported at its lower end on the lower coupling between certain sections of the radiator, and means for securing the foot rest against pivotal movement.

2. The combination with a radiator, of a foot rest pivotally supported on the coupling between certain sections of the radiator, with freedom for radial displacement therefrom, a latch for securing the foot rest in different set adjustments, and a clamp securing the latch to the radiator and for holding the foot rest against removal from its pivotal support.

3. The combination with a radiator, of an arm pivotally mounted on the radiator and having lock notches at its free end, a latch coöperating with said lock notches for hold-

ing the arm in different set adjustments, a clamp for securing the latch to the radiator, and a foot rest carried by the arm.

4. The combination with a radiator, of an arm pivotally mounted on the radiator and having lock notches at its free end, a latch coöperating with said lock notches for holding the arm in different set adjustments, a clamp securing the latch to the radiator, a key engageable with the latch for holding the same in an operative position, and a foot rail carried by the arm.

5. The combination with a radiator, of a pair of laterally spaced arms pivotally mounted on the radiator and having lock notches at their free ends, latches coöperating with said lock notches for holding the arms in different set adjustments, clamps securing the latches to the radiator, and a foot rail carried by the arms.

6. The combination with a radiator, of a pair of laterally spaced arms pivotally mounted on the radiator and having lock notches at their free ends, latches coöperating with said lock notches for holding the arms in different set adjustments, clamps securing the latches to the radiator, and a foot rail carried by the arms with freedom for longitudinal adjustment thereon.

In testimony whereof I affix my signature in presence of two witnesses.

RICHARD S. CHAPMAN.
